UNITED STATES PATENT OFFICE

2,360,670

ELECTRIC SWITCH

Ernest F. Goetz, Schenectady, N. Y., assignor to
 General Electric Company, a corporation of
 New York

Application May 6, 1943, Serial No. 485,873

6 Claims. (Cl. 200—165)

My invention relates to electric switches, more particularly to cutout switches, and has for its object a simple and reliable operating mechanism for limiting the speed of movement of the switch member to a predetermined desirable speed when the operating member is moved at a higher speed.

My invention is especially related to auxiliary small control or interlock switches which are operated by the movable armature of a magnet when the armature approaches its final picked up position. The control switch to which my invention relates may, for example, be in circuit with the operating coil of the armature so as to insert a current limiting resistance in the circuit of the coil when the armature has picked up. When the operating armature is fully loaded, its speed may not be great enough to damage the control or interlock switch. I have found, however, that when the armature does not have applied to it the load which it is designed to operate, the armature accelerates to a very high speed before reaching its fully attracted position, and these high speeds produce excessive vibration in the contact arm of the auxiliary switch, causing it to break.

In accordance with my invention, I provide an operating member for the auxiliary switch which is engaged by the operating armature and which is movable independently of the auxiliary switch. This operating member is biased by a comparatively heavy spring force to a predetermined switching position, and the switch arm of the auxiliary switch is biased against the operating member by a weaker spring which will accelerate the switch arm to a predetermined maximum operating speed which does not damage the switch arm. Thus, in the operation of the device the operating member may be moved at a very high speed by the armature of the magnet, but this high speed movement takes place independently of the switch arm which is moved by the weaker spring at a lower speed without damage to the switch arm.

For a more complete understanding of my invention, reference should be had to the accompanying drawing in which Fig. 1 is a front elevation view with the cover removed of a switch embodying my invention; Fig. 2 is a sectional view taken along the line 2—2 of Fig. 1 looking in the direction of the arrows and showing a cover in place; Fig. 3 is a sectional view along the line 3—3 of Fig. 1 looking in the direction of the arrows; Fig. 4 is a sectional view along the line 4—4 of Fig. 2 looking in the direction

of the arrows; while Fig. 5 is a view in perspective of a bridging contact member embodied in the switch.

Referring to the drawing, in carrying out my invention in one form I provide a metallic operating member 10 pivotally mounted on a fixed pivot 11 on supports 12 and 13 secured to a metal base 14. One arm 10a of this operating member extends through an opening 15 in the base to the exterior where it is engaged for operation of the switch by a projection or arm 16 attached to the lower end of the plunger type armature 17. The armature is shown in its unattracted position. When it is picked up upon the energization of a conventional coil (not shown) the arm 16 engages the part 10a and moves the operating member 10 counterclockwise about the pivot 11, as seen in Fig. 2, until the portion 10a is near the upper wall of the opening 15.

5 The portion of the operating member 10 adjacent the pivot 11 is provided with two spaced apart flanges 18 and 19 which may be integral with the arm 10a. Secured to these flanges integrally, as by welding, are two spaced plates 20 and 21 joined together by a cross or bottom portion 22 provided with an aperture 23. A pin or bolt 24 has its right-hand end, as seen in Fig. 2, secured to the inner side of the base 14 and extending toward the left at right angles therewith 10 centrally through the aperture 23. Surrounding the bolt 24 on the left-hand side of the cross member 22 forming part of the operating member 10 is a relatively strong helical spring 25 having one end bearing on the cross portion 22, 15 and its other end bearing on a fixed spring seat 26 on the bolt. As shown, the bolt extends through an aperture provided for it in an enclosing cover 27 on the exterior of which it is provided with a nut 28 to hold the cover in place 20 on the base. At the top a similar bolt 29 is provided but solely for the purpose of holding the upper end of the cover in place.

This relatively strong spring 25 applies a correspondingly strong force tending to move the operating member 10 clockwise about its pivot and normally holds the arm 10a against the lower edge of the opening 15, which edge acts as a stop for the operating member. Thus, as the armature 17 moves upward, the operating member is moved counterclockwise at a speed corresponding with the speed of the armature, the spring 25 being compressed. This operating member, however, is rugged and compact enough 50 so that it is not damaged by the most severe high

speed operating conditions imposed by the magnet when it is operating a very light load.

Also mounted pivotally on the stationary pin 11 is a switch arm 30 made of electrically insulating material, such as a molded phenolic product. This arm 30 is provided with an aperture 31 through which the bolt 24 extends loosely so that the switch arm, as well as the operating member 22, can move pivotally without engaging the bolt. It is also provided with a recess 32 in its right-hand side, as seen in Fig. 2, surrounding the bolt 24, in which recess is a relatively weak helical spring 33 surrounding the bolt and having its right-hand end bearing on the base 14 and its left-hand end bearing on the switch arm so as to apply a counterclockwise force to the switch arm and hold it against the cross portion 22 of the operating member, the switch arm being provided with a flat surface engaging this cross portion. Also, the lower end of the switch arm 30 is provided with an extension 34, partly cylindrical, provided with an aperture through which the pivot pin 11 extends and lying between the two parallel plates 20 and 21 of the operating member.

At its upper end the switch arm 30 has secured to it a rigid metal support 35, shown more clearly in Fig. 5, on which is mounted a bridging contact or switch member 36. This bridging contact has switch contacts 37 and 38 on its opposite ends which are movable into engagement with stationary contacts 39, only one of which is shown, mounted on the ends of electrically conducting supporting members 40 and 41.

As shown, the contact supporting members 40 and 41 are mounted on projections or ledges provided for them in an insulating support 42 made of a suitable molded electrically insulating material, and held in place by screws as shown. This support 42 has a supporting back wall 43 lying against the support 14 and secured to the support 14 by suitable screws 44 and 45 (Fig. 4), and additional screws 46, only one of which is shown. It is provided with two walls 47 and 48 extending outward from the base on opposite sides of the switch arm 30 and loosely embracing the switch arm, together with two higher walls 49 and 50 on the outside. Between the walls 47 and 49 is the ledge 51 (Fig. 4) forming the support 50 for the contact support 40, while a similar supporting ledge is provided between the walls 48 and 50 for the contact support 41.

Also, the outside walls 49 and 50 are extended around the movable and stationary contacts to form an upper portion or wall 52 which surrounds the stationary and movable contacts. The back wall 43 is extended and joined with this upper wall portion 52. This upper wall portion forms an enclosure in which all arcing takes place and in which the arcs are suppressed.

As shown in Fig. 5, the bridging member 36 is provided at its middle with a laterally extending pin 54 carrying on its outer end a knob 55. This pin extends through an aperture provided for it in the upper end of the support 35 and is surrounded by a helical compression spring 56 which normally holds the bridging member against the end of the support 35, as shown in Fig. 5. Projections 57 and 58 are provided on the support adjacent the lower edge of the bridging member so as to prevent turning of the bridging member from its lateral position on the support. Also, this support is provided with two

bends and an offset connecting portion near its middle. The relation of this support with the contact supports 40 and 41 is such that the movable and stationary contact supporting parts can be removed and put in place again in reversed positions to change the switch from a normally closed one, as shown in the drawing, to a normally open one. Thus, when the support 35 is reversed, the offset portion brings the bridging contacts behind the stationary contact supports 40 and 41, and these latter supports then need only be removed by removing their holding screws, turned over to bring the contacts 37 and 38 into engaging position with the bridging contacts, and then secured again by the screws.

Thus, as previously stated, the operating member 10 can be moved without damage to it at any excessively high speed about the pivot 11, the spring 25 being compressed. The switch arm 30, however, follows at a lower speed determined by the strength of the relatively weak spring 33, the strength of this spring being chosen to assure a maximum speed of operation of the switch arm which does not damage it. I have found that, with the contact support 35 rigidly connected to the operating member 10, after a few hundred thousand operations at excessively high speeds, the contact support 35 broke, apparently by reason of excessive vibration. In this particular case, no damage was caused by excessive hammering of the contacts.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. A switch comprising an operating member mounted for movement, a first means biasing said operating member to a predetermined position, said first means yielding to provide for high speed movement of said operating member in one direction, a switch member movably mounted adjacent said operating member, and means biasing said switch member against said operating member with a force smaller than the opposing force of said first means and for moving said switch member in said direction at a maximum predetermined speed independently of said operating member in the event of movement of said operating member in said direction at a speed higher than said predetermined speed.

2. A switch comprising an operating member mounted for movement, a stop for said operating member, a first spring biasing said operating member against said stop, said first spring yielding to provide for high speed movement of said operating member in one direction, a switch member movably mounted adjacent said operating member, and a second spring for biasing said switch member in said direction against said operating member with a force smaller than the opposing force of said first spring and for moving said switch member in said direction at a maximum predetermined speed independently of said operating member in the event of movement of said operating member in said direction at a speed higher than said predetermined speed.

3. A switch comprising an operating member mounted for movement about a fixed pivot, a stop for said operating member, a relatively strong spring biasing said operating member

against said stop, said spring yielding to provide for high speed movement of said operating member, a switch arm pivotally mounted adjacent said operating member, and a relatively weak spring for biasing said switch arm against said operating member and for moving said switch arm at a maximum predetermined speed independently of said operating member in the event of movement of said operating member away from said switch arm at a speed higher than said predetermined speed.

4. A contactor comprising a fixed pivot, an operating member mounted on said pivot, a stop for said operating member, a relatively strong spring biasing said operating member to a predetermined angular position against said stop, a switch arm pivotally mounted on said pivot, a relatively weak spring biasing said switch arm against said operating member for moving said switch arm at a predetermined maximum speed about said pivot thereby to limit the speed of said switch arm when said operating member is moved away from said switch arm at a higher speed, a movable electric contact carried by said switch arm, and a stationary contact cooperating with said movable contact.

5. A switch comprising a fixed pivot, an operating member mounted on said pivot at a point intermediate its ends, a stop for a first arm of said operating member, a first helical compression spring having one end bearing on a second arm of said operating member thereby to apply a force tending to move said operating member about said pivot until said first arm is brought to rest against said stop, a switch arm mounted on said pivot and extending along the side of said second arm opposite said first spring, a second helical compression spring having one end bearing on said switch arm so as normally to hold said switch arm against said second arm of said operating member with

said operating member with a force smaller than that applied to said second arm by said first spring and for moving said switch arm at a predetermined maximum speed independently of higher speed movement of said operating member away from said switch arm, a movable contact carried by said switch arm, and a stationary contact cooperating with said movable contact.

6. A switch comprising a fixed pivot, an operating member mounted on said pivot at a point intermediate its ends, a stop for a first arm of said operating member, the second arm of said operating member being provided with an aperture, a stationary rod extending through said aperture in a direction substantially at right angles with said pivot, a first helical compression spring on said rod having one end bearing on said second arm thereby to apply a force tending to move said operating member about said pivot until said first arm is brought to rest against said stop, a switch arm made of electrically insulating material mounted on said pivot and extending along the side of said second arm opposite said first spring, a second helical compression spring surrounding said rod and having one end bearing on said switch arm so as normally to hold said switch arm against said second arm of said operating member with a force smaller than that applied to said second arm by said first spring and for moving said switch arm at a predetermined maximum speed independently of higher speed movement of said operating member away from said switch arm, a metal contact carrying member on the movable end of said switch arm, a movable contact carried by said member, and a stationary contact cooperating with said movable contact.
